UNITED STATES PATENT OFFICE

2,518,075

APPARATUS FOR WINDING TUBES

Wayne R. Scherer, Trooper, Pa., assignor, by
mesne assignments, to Taylor Fibre Co., Nor-
ristown, Pa., a corporation of Delaware

Application March 1, 1946, Serial No. 651,361

5 Claims. (Cl. 93—81)

1

This invention relates to an improvement in the method and apparatus for winding tubes of paper or other material impregnated with a synthetic material, as phenol formaldehyde resin, whereby the tightness of the winding is only limited by the strength of the stock from which the tube is wound.

It was known heretofore to wind the paper strip on a driven mandrel supported between a pair of heated rolls, the tube and mandrel being retained in position between the heated rolls by means of a weighted roll which retained the mandrel and tube thereon in winding contact with the rolls during the winding. As the strip was passed over one of the heated rolls to the mandrel, then between the mandrel and the other heated roll and thereafter under the weighted roll, so the tension on the strip tends to draw the mandrel away from the winding area between the mandrel and the rolls, tending to deflect the tube during the winding causing the formation of non-uniform tubes.

One of the objects of my invention is the provision of a method and means whereby a uniform and high tension across the full width of the material is maintained.

Another object of my invention is the provision of means whereby the tension of the material passing to the tube being wound, retains the tube in winding contact with the heated rolls so that the tightness of the winding of the tube is controlled entirely by the tension of the strip passing to the mandrel.

Another object of my invention is the provision of means whereby the heated rolls can readily be separated for the insertion of the strip between the rolls, for connecting the strip to the mandrel and locking the rolls in fixed relation to each other during the winding.

Another object of my invention is the provision of means for retaining the end of the strip adjacent to the heated rolls when severed after the completion of a tube.

Another object of my invention is the provision of means whereby both sides of the strip contact with a heated roll before entering the winding area.

Referring to the accompanying drawings, illustrating one form of apparatus for winding tubes in accordance with my invention and in which:

Fig. 1 is a vertical section through the winding machine;

Fig. 2 is a side elevation showing the mandrel driving mechanism and a portion of one of the heated rolls;

Fig. 3 is a view similar to Fig. 1 showing another form of winding machine, and

Fig. 4 is a sectional view on the line 4—4 of Fig. 3.

ment of the bell crank arm 26 and the roll 16 towards or from the roll 14.

The arc-shaped upper face of each bearing member 30 is provided with recesses *a* and *b* adapted to be engaged by the pawls 48 for retaining the roll 16 in either of its positions relative to the roll 14.

The various members of the apparatus when winding a tube are in the positions shown in full lines in Fig. 1, in which a strip S is drawn from a roll R by the rotation of mandrel 18 to wind a tube T thereon while supported by the rolls, and which is rotated as hereinafter described. The strip S is drawn from the roll R about the several rotatable tensioning rods 56, shaft 24, between the rolls 14 and 16, which are rotated by frictional contact with the tube T being formed about the mandrel, and is held in contact therewith by the tension on the strip S caused by the zigzag course of the strip from the roll R to the mandrel, together with a weighted roll 60 in contact with the roll R.

The roll 60 is mounted on a shaft journaled in an arm 62 at each end of the frame 10 and pivoted thereto at 64. The outer ends of the arms 62 are connected to each other by a cross bar 66 and 68 is a weight supporting bar extending from the central portion of the cross bar 66 on which a hook 70, having removable weights 72 supported thereon, whereby the weight on the roll 60 may be varied to vary the tension on the strip.

Extending from one end member 10 of the frame to the other below rolls 14 and 16 and back of the strip S in its passage to the rolls 14 and 18, is a sheet metal member 76 arranged to catch and support the end of the strip S, when the strip is severed from the mandrel, and coacting with said member 76 is a clamping rod 78, connected at its ends to a pair of levers 80, one at each end of the machine pivoted on the rod 28, the arrangement being such that when the strip S is severed, the rod 78 will clamp the end of the strip against the member 76, and prevent the unthreading of the strip about the tensioning rods.

The driving mechanism for the mandrel is supported on an extension frame at the side of the main frame, formed of an upright member 11, which is connected to one of the end members 10 of the frame, by the plate 20, and 82 is a plate below plate 20 connected to members 10 and 11.

Supported on plate 82 is a motor 84 connected to reducing gearing in a casing 86, and 90 is a sprocket wheel mounted on a shaft 92 extending from the reducing gearing.

Mounted in bearings 94 on plate 20 is a spindle driving shaft 96 having a sprocket wheel 98, connected thereto and which is arranged to be driven by a sprocket chain from the sprocket wheel 90.

The winding mandrel 18 is arranged to be driven from a shaft 100 by a flexible shaft 100 having a chuck 102 on one end thereof, for the reception of one end of the mandrel 18, and which is connected to the shaft 100 by a flexible coupling 104 and 106 is a similar coupling between shafts 100 and 96.

The shaft 100 is provided with a slip connection 108 between coupling members 104 and 106, for permitting the variation in the length of the shaft 100, as the tube T increases in size during the winding.

In the form shown in Figs. 3 and 4 the various members of winding and tensioning means are supported on a frame comprising end members

10', which are connected to each other by spaced angle members 12' as in the structure shown in Fig. 1.

Mounted for relative rotation in bearings at opposite ends of the machine are hollow rolls 14' and 16' arranged to be heated in any desired manner for heating the successive convolutes of the strip during the winding on a mandrel 18', which is supported by both the rolls and are arranged to be frictionally rotated by the tube being wound on the mandrel.

Both rolls 14' and 16' are supported in fixed bearings 19' extending upwardly from a plate 20' forming a continuation of the frame, on which the driving mechanism for the mandrel 18' is supported as shown in Fig. 2.

The bearings 19' are so arranged that the rolls may be readily removed for replacement by rolls of different diameters to vary the distance between the rolls, whereby the mandrel receiving space between the rolls can be provided for mandrels of different diameters or for mandrels having tube rolling surfaces of different lengths.

Rotatably mounted in the end members 10' of the frame are rolls 120 and 122 which are formed of rubber molded on a shaft or a rubber facing or similar material mounted on the faces of the rolls to frictionally engage the strip passing to the winding mandrel as hereinafter described.

Extending between the rolls 120 and 122 and rolls 14' and 16' is a plate 124, which is suitably supported from the frame end members 10' and extends the full length of the space between the end members 10'.

Extending below the plate 124 are electric heating means 126, although any form of heating means for heating the plate may be provided.

Connected to the shaft of roll 120 beyond the outer face of the one end plate 10' is a pulley 128, shown in dotted lines in Fig. 3, the face of which is engaged by a brake shoe 130, pivotally connected to one end of a brake lever 132. The brake lever 132 is pivotally mounted on a trunnion 134 connected to the end plate and extending outwardly therefrom, and supported on the end of the brake lever 132 opposite the brake shoe is a weight supporting hook on which removable weights may be supported for the purpose hereinafter described.

Supported on the frame at the side of roll 14' is a platform 140 for supporting the mandrels and from which the mandrels are rolled into winding position between rolls 14' and 16', and to which the wound tubes on their mandrels can be rolled from between rolls 14' and 16'.

As shown in Fig. 3, a portion of a tube T' is wound on the mandrel 18' and formed from a strip S' drawn from a roll R', which first passes around a tension roller 56', then between rollers 120 and 122, over the plate 124, where it is heated and then passes to the mandrel 18' between rolls 14' and 16'.

A friction roller 60' journaled in an arm 62' pivotally connected to each end member 10' as described in the structure shown in Fig. 1, and having supported thereon adjustable weights, to supply sufficient friction to prevent overrunning of the strip between the roll R' and rolls 120 and 122.

The rolls 120 and 122 frictionally engage the strip S' and are rotated thereby during the withdrawing of the strip from the roll R', while the final or desired tension on the strip for the winding on the mandrel above that caused by the friction on the roll R' and the passage of the strip

S' from the roll R' to rolls 120 and 122 is controlled by adjusting the pressure of the brake shoe 130 against the brake wheel or pulley 128.

The threading and winding of the strip S', as shown in Fig. 3, is accomplished in the following manner:

After the roll R' has been positioned in its supports, the strip S' is passed around tension roller 56', then between rollers 120 and 122, roller 120 is then rotated by rotating (by hand) pulley 128 to feed the strip to the mandrel and after the strip has been started on the mandrel, the mandrel is rotated by the shaft 100' through the medium of the clutch 102', to which the mandrel has been secured as described in connection with Fig. 2.

When the strip has been connected to the mandrel and the proper tension by the brake has been applied to the strip S', it is drawn from roll R', is heated to the desired temperature while passing over the plate 124, and as the tightness of the winding can be controlled by the tension on the strip, which can be varied by the pressure of the brake shoe 130 on pulley 128.

The tension placed on the strip during the winding will draw the tube into contact with the heated rolls 14' and 16' so the successive convolutes of the strip will be firmly pressed into contact with each other and cured during the winding.

When the wall thickness of the wound tube has been reached, the winding of the strip is stopped, the strip is severed at any point between the two sets of rolls, and after severance of the strip, the rolls 14' and 16' may be rotated a sufficient length of time to fix and cure the short severed end of the strip to the wound tube.

One of the advantages of my invention results from the provision of tube winding mechanism whereby the tension on the strip being wound on a rotating mandrel, draws the tube being wound directly into contact with both heating and supporting rolls, and thereby prevents any deflection of the tube during the winding, and thus produces tubes of uniform diameters throughout their length.

Another advantage results from so delivering the strip to the winding mandrel, that the strip is heated before the strip is engaged in winding relation with the tube as it is being wound, and under a tension only limited by the strength of the strip, and whereby an equal pressure is applied along the entire length of the tube as well as during the entire winding period of the tube, so that a tube of equal density throughout its entire wall is produced.

What I desire to secure by Letters Patent is:

1. Means for winding tubes from strip material, comprising a pair of mandrel supporting rolls, a mandrel on which the tube is to be wound, means to rotate the mandrel while positioned on both rolls, means for guiding the strip to the mandrel between the rolls, means for tensioning the strip, pivoted means for supporting one of said rolls for moving said roll away from the other roll when threading the strip between the rolls and for returning said roll, and means for locking the pivoted means when the movable roll has been moved into operative relation to the other roll after threading.

2. Means for winding tubes from strip material, comprising a pair of mandrel supporting rolls, a mandrel on which the tube is to be wound, means to rotate the mandrel while positioned on both rolls, means for guiding the strip to the

mandrel between the rolls, means for tensioning the strip, a pair of pivoted bell-cranks for supporting one of said rolls, means for shifting the bell-cranks for moving said roll away from the other roll when threading the strip between the rolls and for returning said roll after threading, and means for locking the bell-cranks to retain the movable roll relative to the other roll after being returned.

10 3. Means for winding tubes from strip material, comprising a pair of mandrel supporting rolls, a mandrel on which the tube is to be wound, means to rotate the mandrel while positioned on both rolls, means for guiding the strip to the mandrel between the rolls, means for tensioning the strip, pivoted means for supporting one of said rolls for moving said roll away from the other roll when threading the strip between the rolls and for returning said roll, means for locking the pivotal means when the movable roll has been moved into operative relation to the other roll after threading, and a clamp between the rolls and the tensioning means for holding the strip in position between the rolls after threading before being wound on the mandrel.

20 4. Means for winding tubes from strip material, comprising a pair of mandrel supporting rolls, a mandrel on which the tube is to be wound, means to rotate the mandrel while positioned on both rolls, means for guiding the strip to the mandrel between the rolls, means for tensioning the strip, pivoted means for supporting one of said rolls for moving said roll away from the other roll when threading the strip between the rolls and for returning said roll, means for locking the pivotal means when the movable roll has been moved into operative relation to the other roll after threading, and a clamp between the rolls and the tensioning means for holding the strip in position between the rolls after threading before being wound on the mandrel.

25 30 5. Means for winding tubes from strip material, comprising a pair of mandrel supporting rolls, a mandrel on which the tube is to be wound, means to rotate the mandrel while positioned on both rolls, means for guiding the strip to the mandrel between the rolls, means for tensioning the strip, pivoted means for supporting one of said rolls for moving said roll away from the other roll when threading the strip between the rolls and for returning said roll, treadle mechanism connected to the roll supporting means for moving said movable roll relative to the other roll and means for locking the treadle mechanism when the movable roll is moved towards the other roll after threading to retain the roll in rolling relation with the mandrel.

35 40 45 50 55 60

5. Means for winding tubes from strip material, comprising a pair of mandrel supporting rolls, a mandrel on which the tube is to be wound, means to rotate the mandrel while positioned on both rolls, means for guiding the strip to the mandrel between the rolls, means for tensioning the strip, pivoted means for supporting one of said rolls for moving said roll away from the other roll when threading the strip between the rolls and for returning said roll, treadle mechanism connected to the roll supporting means for moving said movable roll relative to the other roll, a treadle frame pivotally mounted on the treadle mechanism, and a pawl carried by the treadle frame for locking the treadle mechanism when the movable roll is moved towards the other roll after threading to retain the roll in operating relation with the mandrel.
